UNITED STATES PATENT OFFICE.

FRANK VAN ALSTINE, OF SACRAMENTO, CALIFORNIA.

ATTACHMENT FOR LADDERS.

No. 812,620.

Specification of Letters Patent.

Patented Feb. 13, 1906.

Application filed May 23, 1905. Serial No. 261,777.

To all whom it may concern:

Be it known that I, FRANK VAN ALSTINE, a citizen of the United States, and a resident of Sacramento, in the county of Sacramento and State of California, have invented a new and Improved Attachment for Ladders, of which the following is a full, clear, and exact description.

This invention relates to attachments for ladders; and it consists, substantially, in the details of construction and combinations of parts hereinafter more particularly described, and pointed out in the claims.

The invention has reference more especially to attachments for ladders of the store-service type, though applicable to other types; and one of the principal objects thereof is to overcome numerous disadvantages and objections frequently attending the use of many forms of such ladders as hitherto devised and employed.

A further object is to provide a store-service ladder with means whereby goods in stock within a store or other place may be taken from the supporting-shelves therefor and readily examined or handled at any height, either to ascertain the amount of stock on hand or make up orders or sort or rearrange the goods without the operator having to descend the ladder with the goods for that purpose.

A still further object is to provide an attachment for store-service ladders for the purposes named which is simple in its embodiment and cheap to manufacture, besides being easily and quickly applied, thoroughly effective and reliable in use, and possessing the capacity for long and repeated service.

The above and additional objects are attained by means substantially such as are illustrated in the accompanying drawings, forming a part of this specification, in which similar characters of reference indicate corresponding parts in all the views.

Figure 1 is a view in perspective showing a store-service or other ladder having my improvements embodied in connection therewith. Fig. 2 is a vertical sectional elevation showing the movable table or platform of my improvement in its outward or horizontal position; and Fig. 3 is a similar view showing the movable table or platform, together with parts with which the same is connected, as carried to the innermost position thereof,

when suspended from one of the rungs or steps of the ladder.

Before proceeding with a more detailed description it may be stated that in the form of my improvements herein shown I employ specially-constructed duplicate hangers by which the structure of my improvements may be firmly caught upon and suspended from any one of the steps or rungs of an ordinary store-service or other ladder, combined with which hangers are duplicate outwardly and inwardly swinging brace members of special construction, in movable connection with the upper ends of which are the specially-devised side members of a table or platform having movable relation to said hangers. The construction and organization of the several elements or parts of the structure are such that, while standing on one of the steps of the ladder, the operator may pull the table outwardly substantially to a horizontal position before him, so as to enable him to handle goods thereon for any purpose desired, and then when he has finished with the use of the table the same may be folded inwardly partly to the under or rear side of the ladder, so as not to be in the way nor present an unsightly appearance. The structure may be instantly detached from the step of the ladder in entirety, to be shifted or caught upon another step, according to the height at which it may be necessary to handle the goods.

While I have herein represented my improvements in a certain preferred embodiment, it will be understood, of course, that I am not limited thereto in precise detail, since immaterial changes therein may be made coming within the scope of my invention.

Reference being had to the drawings by the designating characters marked thereon, 1 represents ordinary shelving, such as is ordinarily employed in stores, warehouses, and other places for supporting various kinds of stock or merchandise, and 2 represents an ordinary ladder of the store-service type, it being understood that ladders of this kind are usually provided with means by which they may be shifted to one side or the other longitudinally of the shelving while the operator is standing thereon in the examination or handling of goods. My improvements comprise duplicate hangers 3, which, as shown, are preferably constructed of T or angle iron,

said hangers being formed with downwardly extending substantially straight parallel members 4, terminating at the upper ends thereof with hooks 5, which in the use of the structure are caught upon the step or rung 6 of the ladder, as shown, the space between the opposing faces 7 and 8, respectively, of the parallel members 4 and the said hooks 5 gradually decreasing in width upwardly, thus 10 to cause the step of the ladder to become wedged therein by the weight of the structure thereon, and thereby effecting a secure support for the structure in its position upon the ladder.

15 Formed on the inner faces of the upper portions of the parallel members 4 of the hangers at points near to the bends 9 therein are pins or headed rivets 10, which are received in corresponding arc or segmental slots 12 in 20 parallel side members 13 pendent from the under side of a table or platform 14 at or near the ends of the latter, said side members 13 being preferably constructed of flanged metal and having the inner portions 15 there- 25 of, Fig. 1, secured to the table or platform in such a manner as to prevent any tendency to cracking or splitting of said table-platform in use. The parallel side members 13 of the table or platform are also formed at the outer or 30 forward ends thereof with corresponding slots or elongated openings 16, in which work or are received headed pins or rivets 17, projecting from the inner faces of the upper end portions of duplicate parallel brace members 18, the 35 lower extremities of which are adjustable in corresponding openings 19, formed in the straight parallel members 4 of the hangers, by means of other headed pins or rivets 20 or in any other suitable way, said brace mem- 40 bers 18 being capable of folding inwardly sub- stantially parallel with the members 4 of the hangers when the table or platform 14 is carried inwardly and downwardly by the operator to the position shown in Fig. 3.

45 When the table or platform is carried outwardly, Fig. 2, to a substantially horizontal position before the operator on the ladder, the brace members 18 serve to rigidly maintain the table or platform in such position 50 while the goods are being handled thereon. The slots 17 permit of the necessary movements of the several parts or elements by which to effect the several adjustments desired in use, and it may be stated that the 55 purpose of having the lower extremities of the brace members 18 adjustable with reference to the parallel members 4 of the hangers is to enable a ready conformability to be had to the varying angles of inclination at which 60 the ladder may be placed.

For the purposes of rigidity and strength I preferably provide a connecting-brace 21 between the said parallel members 4 of the hangers 3, together with a similar connecting- 65 brace 22 between the brace members 18 for

the table or platform, it being understood that all the parts or elements of the structure excepting the table or platform are preferably constructed of metal of suitable lightness and durability.

If desired, the parallel side members 4 of the hangers 3 may be straight throughout their length, or they may be curved somewhat inwardly, as indicated at 23, either as may be preferred in practice. The connecting-brace 21 between the said side members 4 of the hangers is so located with reference to the steps 6 of the ladder as not to encounter the same, and it is thought that the construction and operation of my improvements will 75 be fully understood without further detailed description.

When the parts are in the position indicated in Fig. 3, they are entirely out of the way and do not present an unsightly appearance, and should it be desired to entirely remove the structure or attachment from the ladder this may be readily done by simply lifting the same upwardly and carrying it 80 forwardly in a manner quite apparent.

It will be observed that the lower edges of the parallel side members 13 of the table or platform 17 are curved at 24 on lines parallel with the curvatures of the slots 12 therein and also that the inner faces of the hooked 90 portions of the hangers 3 are formed or provided with projections 25, over which the said lower curved edges 24 of the side members 13 of the table or platform ride in the adjustments of the table or platform to and 95 from the position thereof indicated in Fig. 3. When in this latter position, the said projections 25 serve as supports for the lower edges of the side members of the table, as is apparent, and prevent any looseness between the 100 parts of the structure.

Instead of using the structure while standing on the ladder it is apparent that the operator may stand on the table or platform while performing such duties as may be necessary with the shelving or goods thereon. The table or platform may be easily shifted to either its outward or inward position by a light application of the toe of the foot or in any other way.

Having thus described my invention, I claim as new and desire to secure by Letters Patent—

1. An attachment for ladders, comprising means adapted to be suspended from a step of the ladder, a table having connections therewith, movable outwardly and inwardly with reference thereto, and braces for the table in its outward position, movable inwardly and outwardly therewith.

2. An attachment for ladders, comprising means adapted to be suspended from a step of the ladder, a table having connections therewith and movable outwardly and inwardly with respect thereto, and having par-

- allel side members formed with corresponding segmental slots, said means having inwardly-projecting devices working in said slots, braces adapted to move outwardly and inwardly with the table, having movable connections with the forward ends of the said side members of the table, and also having adjustable connections with parallel members of the means referred to.
- 10 3. An attachment for ladders, comprising hangers adapted to be suspended from a step of the ladder, a table having connections therewith and movable outwardly and inwardly with respect thereto, and also having parallel side members formed with corresponding segmental slots, the lower edges of said side members being curved in corre-
- spondence with the edges of the slots, said hangers having inwardly-projecting devices working in the slots, and similar projections on which ride the lower edges of the said side members, braces for the table, movable outwardly and inwardly with respect to the hangers, and having connections with the forward ends of the said side members of the table, together with adjustable connections with parallel members of the said hangers.
- 15 In testimony whereof I have signed my name to this specification in the presence of two subscribing witnesses.

FRANK VAN ALSTINE.
